No. 764,507.

PATENTED JULY 5, 1904.

T. H. SYMINGTON.
RAILROAD JOURNAL BOX.
APPLICATION FILED JULY 30, 1901.

NO MODEL.

UNITED STATES PATENT OFFICE.

THOMAS H. SYMINGTON, OF BALTIMORE, MARYLAND.

RAILROAD JOURNAL-BOX.

SPECIFICATION forming part of Letters Patent No. 764,507, dated July 5, 1904.

Application filed July 30, 1901. Serial No. 70,300. (No model.)

To all whom it may concern:

Be it known that I, THOMAS H. SYMINGTON, a citizen of the United States of America, and a resident of Baltimore city, State of Maryland, 5 have invented certain new and useful Improvements in Railroad Journal-Boxes, of which the following is a specification.

My invention relates to a journal-box for car-axles of the usual round or square bottom 10 form, which is familiarly known as the "Master Car-Builders" type.

It consists of a box square at the top and round or square at the bottom, having an aperture in the rear through which the axle 15 passes and a door in the front by which the waste and lubricating oil or grease may be inserted. As the journal revolves in use the oil, being liquid or converted into liquid by the heat of the journal, falls to the bottom of 20 the box, while the waste rolled up by the motion of the journal is packed on one side of the box and frequently drawn entirely away from the oil, so that a box will often become heated, although it contains a large quantity 25 of oil and waste.

My invention consists in the introduction into the interior of the journal-box of two or more radial ribs which are cast integral with the box and which are located at or about the 30 lower corners of the box and which project inward toward the journal as far as the shape of the journal will permit. They are made either straight upon their edges or preferably serrated upon their edges and are parallel or 35 approximately parallel to the axis of the journal, the object being to hold the waste when packed into the journal-box in contact with the journal and prevent it from rolling up on one side of the box in the direction of travel 40 of the journal. The ribs form, with the side wall of the box, a well upon the side of the box, which will contain the oil and which when the box is packed with waste may be 45 filled with oil and a less quantity of oil employed than would be the case if the ribs were omitted. Furthermore, these ribs by their position in the box strengthen the box and it is possible to make the box lighter than has heretofore been possible.

50 In the drawings similar numerals of refer-

ence indicate similar parts throughout all figures.

Figure 1 is a vertical transverse section of the box and axle, showing waste and oil in the box. Fig. 2 is a vertical longitudinal section of the 55 box without the journal. Fig. 3 is a horizontal longitudinal section of the box, showing the ribs in plan.

Referring to Fig. 1, 1 is a journal-box having an opening in the rear 2, through which the axle 3 is passed. The box, as shown in this figure, is round at the bottom 4, and on the interior at the lower corners of the box are longitudinal ribs 5 5, which extend from one end to the other of the box and are located approximately radial of the journal. 66 are a pair of ribs also longitudinally located on the interior of the box on each side and lying in the same horizontal plane and in a plane which is parallel to the axis of the journal 70 and very close to the plane of the axis of the journal.

The edges of the ribs 5 5, as shown in Figs. 2 and 3, are made of a shape to conform to the contour of the axle, the bearing-surface 75 of the axle being of smaller diameter than the head and shoulder. For this reason the ribs 5 5 are made on the edge of a shape which will conform to the shape of the axle.

As shown in Figs. 2 and 3, the portion of 80 the ribs 5 5 which is opposite the bearing-surface of the axle is provided on its edges with a series of notches 77.

In practice the operation of my invention is as follows: When waste is packed into the 85 journal-box under the axle and between the ribs 5 and 6 on each side of the axle, it will be held by those ribs and prevented from passing from one side to the other of the journal-box and rolling up wholly on one side, and 90 it will also be held and prevented from riding up under the bearing-block, which rests upon the top of the axle, and thus the packing will be enabled to perform its function for a longer period of time and with a smaller quantity of 95 lubricant than would be the case with any other construction. The serrated edges of the ribs 5 5 hold the waste, which may be packed over them against the journal, and prevents lateral motion of the waste, so that it will not 100

ride toward either end of the box, but will remain where it is placed by the oiler.

It will of course be understood that the lower set of ribs 5 5 might be dispensed with 5 and the ribs 6 6 located at any desired position on the sides of the box.

Having thus described my invention, what I claim as new, and desire to secure by Letters Patent, is—

- 10 1. A railway journal-box of standard type having a pair of ribs integral with said box and projecting inwardly toward the journal at an angle to each other and in lines approximately radial of the journal, the space between the ribs being open, whereby packing may be inserted between the ribs and under the journal without removing the journal from the box, said ribs forming the upper surface of a space to be packed with waste.
- 15 2. A railway journal-box of standard type, having a pair of ribs integral with said box projecting inwardly toward the journal at an angle to each other and in lines approximately

radial of the journal, the ribs extending in the box beyond the end of the journal, whereby 25 packing may be inserted under the journal and between the ribs without removing the journal from the box, the ribs being provided upon their edge with serrations and notches, said ribs forming the upper surface of a space to 30 be packed with waste.

3. A railway journal-box of standard type, having a pair of ribs integral with said box and projecting inwardly toward the journal at an angle to each other, the space between the 35 ribs being open whereby packing may be inserted between the ribs and under the journal without removing the journal from the box, said ribs forming the upper surface of a space to be packed with waste.

Signed by me at Baltimore, Maryland, this 25th day of July, 1901.

THOMAS H. SYMINGTON.
